UNITED STATES PATENT OFFICE

OLIVER SELLE, OF ST. LOUIS, MISSOURI

DESIGN FOR A LINK CHAIN

Application filed August 6, 1930. Serial No. 36,575. Term of patent 7 years.

To all whom it may concern:

Be it known that I, OLIVER SELLE, a citizen of the United States of America, residing in the city of St. Louis, in the State of Missouri, have invented a new, original, and ornamental Design for a Link Chain, of which the following is a specification, reference being had to the accompanying drawing, forming a part thereof.

The drawing is an enlarged front elevation of a link chain, showing my new design.

I claim:

The ornamental design for a link chain, as shown.
